UNITED STATES PATENT OFFICE.

LAWRENCE L. BROWN, OF CHICAGO, ILLINOIS.

DISPLAY STAND.

Application filed November 25, 1925. Serial No. 71,396.

This invention relates to display stands standardized form of bending and the width especially adapted for various kinds of small merchandise such as candies, gum, or the like. The chief objects of this invention are to produce a simple, lightweight stand which is of neat appearance and at the same time is substantial in construction; and also to produce a stand which may be made at low cost of stamped sheet metal and formed 10 wire parts.

An illustrative embodiment of the invention is shown in the accompanying drawings, in which:

Figure 1 is a perspective drawing of the 15 display stand.

Fig. 2 is a front elevation of the same.

In this invention a strip of sheet metal is bent and folded into stair-step form to provide the shelves, and a portion of the 20 wire frame work is threaded through the steps.

In the drawings is shown an inclined series 1 of shelves 2 supported on the wire frame work 3. The sheet metal strip, from 25 which the shelves are formed, is bent forwardly at 4, folded back at the front edge 5 of the shelf and carried back in the shelf bottom portion 6 which is bent upwardly at 7 to form a riser 8. At the upper end 30 of the riser 8 the metal is again bent forwardly, folded back to form the succeeding step and then bent upwardly for the next riser. The succeeding shelves of the series are formed in the same manner, and at the 35 end of the top shelf 9 a vertical back portion 10 is provided. The outer edge of each shelf may be inclined upwardly, as shown, to prevent the goods from sliding forwardly, and to serve as a further reinforcement for 40 stiffening the shelf. Joining the riser into the mid-portion of the next succeeding shelf provides efficient reinforcement for that portion of the shelf, and the back edge of the shelf is well stiffened by the bend 7.

The frame work 3 is made up of two triangular wire frames 11 which are joined at the rear lower corner to the cross bar 12. One side 13 of each triangle is threaded 45 through holes in each of the shelves to 50 secure the frame to the shelves and to hold the sheet metal strip from being deformed. The wires 13 also provide sides or lateral retainers for each shelf.

The sheet metal portion is formed so that 55 the member may be duplicated in large quantities. Suitable dies are used for the

width may be varied by selecting different stock strips. The wire for the frames 3 is cut to length, bent at the corner 14, threaded 60 through the holes in the shelves, and then bent downwardly to form the rear leg 15. The ends of the wire are then joined to the ends of the cross bar at the rear corners 16. In this manner the stand is completely 65 assembled and is then ready for use. The rear portion 10 may be utilized for labels, and the upturned front edges 2 of the shelves may be used for the names of the various 70 grades of goods, as indicated in the drawings.

Although but one specific embodiment of this invention has been herein shown and described, it will be understood that numerous details of the construction shown may 75 be altered or omitted without departing from the spirit of this invention.

I claim:

1. A display stand comprising a receding series of shelves formed of a continuous 80 strip of material, and a wire frame comprising two triangular members having the one side thereof threaded through the shelves to connect the frame to the shelves and to form side retainers for each shelf. 85

2. In a display stand a series of shelves formed in a continuous strip of material bent to form a first shelf, then bent upwardly at the rear of the shelf to form a riser, then bent forwardly and folded back 90 upon itself to form a second shelf, then similarly bent upwardly, forwardly and back to form the succeeding risers and shelves of the series, and a wire frame having a portion of the wire threaded through 95 the shelves for attaching the frame to the shelves and for providing side retainers for each shelf.

3. A display stand comprising a receding series of shelves formed of a continuous 100 strip of material bent and folded to form the shelves, each of said shelves having riser portions joining into the middle portion of the next succeeding shelf to brace the same, a frame for supporting said series of shelves, 105 and a support comprising two triangular frames having one side of the triangle threaded through the shelves to brace the shelves and provide lateral retainers.

Signed at Chicago this 13th day of Nov., 110 1925.

LAWRENCE L. BROWN.
